Primary Examiner — Brett Miller*Assistant Examiner* — Jessica M Gebhart(74) *Attorney, Agent, or Firm* — Saliwanchik, Lloyd & Eisenschchen(57) **CLAIM**

The ornamental design for a foot for walking stick, as shown and described.

DESCRIPTION

FIG. 1 is front left side perspective view of the foot for walking stick showing my new design;

FIG. 2 is a rear right side perspective view thereof;

FIG. 3 is a front elevation view thereof;

FIG. 4 is a rear elevation view thereof;

FIG. 5 is a right side elevation view thereof, the left side view is a mirror image thereof;

FIG. 6 is a top plane view; and,

FIG. 7 is a bottom plan view.

The dash broken lines represent portions of the foot for walking stick that form no part of the claimed design. The long dash-short dash broken lines represent boundary lines of the claimed design and form no part thereof. The drawings contain a symbolic break. The portions between the break lines form no part of the claimed design.
